UNITED STATES PATENT OFFICE.

ALBERT H. NELLER, OF FAIRFIELD, IOWA.

HINGE FOR GATES AND OTHER CLOSURES.

Application filed January 9, 1922. Serial No. 527,897.

To all whom it may concern:

Be it known that I, ALBERT H. NELLER, a citizen of the United States, residing at Fairfield, in the county of Jefferson and State 5 of Iowa, have invented a new and useful Improvement in Hinges for Gates and Other Closures, of which the following is a specification.

My invention relates principally to hinges 10 for the closures of animal pens and the like, which may be readily adjusted to fit adjacent portions of the pen and the closure, and it consists of an improved form of the hinge members which may be applied to said 15 parts, one of them being held in fixed relation and the other adjustable and also of an improvement in the details of the same which will be described herein, and will be more definitely set forth in the claims.

Referring to the drawings forming a part 20 of this specification, Fig. 1 is a side elevation of a gate and adjoining portions of the panel of an animal pen with a gate and hinges embodying the features of my invention.

Fig. 2 is an enlarged horizontal section on line 2—2 of Fig. 1. Figs. 3 and 4 are transverse sections on lines 3—3 and 4—4 respectively of Fig. 2, the cut away portions of Fig. 2 being replaced to make it complete 30 as in Fig. 1. Fig. 5 is a side elevation of a modified form of hinge adapted to be used on square or flat side rails, or on siding when used in the construction of the enclosure.

Referring to the drawing, A represents the 35 side rails of a gate made of tubular material and B the adjacent side rails of the panel of an animal pen, also made of tubular material. The fillers of the gate having their ends connected to top and bottom rails D are represented by C, and the fillers in the panel of the pen having their ends connected to the top and bottom rails F are represented by E. The side rails B are generally set in a curb G, and the top and bottom rails of the 40 gate are connected to the side rails A by the elbows H.

I represents the main member of the hinge which has a mating portion J between which, one of the side rails of the gate is clamped 45 by means of bolts K. The main member I is provided with an extension adjustable longitudinally consisting of two parts L inserted between the inner ends of the main member and its mating portion. This extension is adapted to encircle an adjacent 50 filler and is clamped thereon by the smaller

bolt M and also by the adjacent bolt K passed through the inner ends of the main member I and its mating portion J. The inserted ends of the adjustable extension L 60 is slotted where the bolt K passes through it as shown, whereby it may be adjusted to suit the distance of the filler from the side rail. This arrangement will hold the main member of the hinge in fixed position on the 65 gate, or the closure to which it may be attached.

A pivot member consisting of a main part N and a clamping part O is placed on one of the side rails of the panel adjacent to the 70 hinge member I, and is held thereon by tightening the bolt P which is passed through the outwardly extending ends of the parts N and O. The other end of the part O is adapted to catch over a rib Q on the adjacent end of the part N, and when the bolt P is tightened it will clamp the parts N and O securely on the side rail B. Two or more similar hinges are used to support the gate, said hinge or hinges being placed upon the 80 side rail of the gate and connected to the side rail or post of the panel in a similar manner. A latch R adapted to contact with a catch S applied to an opposite portion of the panel, may be pivoted to one of the fillers and be 85 provided with a lock T, all in the usual manner.

If the opening in the panel where the gate is to be placed should vary to a certain extent and be a little wide or a little narrow for the gate, this may be corrected by adjusting the pivot member on the side rail B. If a little wide, the forked end N' of the pivot member may be set a little closer to the gate by torsional movement on the 95 side rail which may be had by loosening the bolt P and twisting the parts N and O around on the cylindrical side rail until the pivot bolt U occupies the proper position. If a little narrow this may be corrected by 100 twisting the parts N and O on the side rail in the opposite direction. The pivot bolt U being only a short distance from the side rail B it will be securely held in place when the bolt P is tightened and the ends N' in 105 which the bolt is inserted, standing at approximately right angles to the plane of the gate, the pivot may be adjusted back and forth to some extent without getting it out of proper alignment.

The main member I, the outstanding end of which is pivoted to the pivot member N,

being secured by the pivot bolt U in fixed relation to the gate or other closure used, and the end of the adjustable pivot member in which said pivot bolt is inserted being 5 close to the side rail B, the pivot will be securely held in position and will not be so liable to become disarranged as if the pivot was approximately half way between the side of the panel and the gate, and the hinge 10 member was also adjustable on the side rail of the gate.

Fig. 5 is a modified form of my hinge which is adapted to be applied to enclosure having square or flat sided material, V being the side rail of the closure and W the adjoining side rail of the enclosure. X represents the main hinge member which may be secured to the member V by bolts or screws in the usual manner. Y represents 20 the pivot member which is preferably a flat piece of metal with outstanding lugs Y' having holes therein for the reception of the hinge bolt to which the main hinge member is pivoted. The pivot member Y is provided with slots Z through which the bolts connecting it to the member W are passed. The hinge may be adjusted by loosening these bolts and sliding the pivot member in or out on the bolts passed through these 25 slots, so as to accomplish a result similar to twisting the members N and O on the side rail B.

The latch R is preferably made long enough so it may be adjusted in the catch 30 S without being drawn away from it. The hinge is exceedingly simple and is efficient and reliable in operation.

What I claim is:

1. In hinges for gates, doors and the like, 35 forming closures, a hinge member secured to the closure in fixed relation thereto and its pivot end extending out beyond an adjacent edge of the structure to which the

closure is applied, a pivot member adjustably applied to said structure and means to 45 pivotally connect the hinge member and the pivot member together.

2. In hinges for gates, doors and the like, forming closures, a hinge member secured to the closure in fixed relation thereto, and 50 its pivot end extending out beyond the adjacent edge of the structure to which the closure is applied, a side-rail cylindrical in cross-section on said edge of the structure, a pivot member applied to said cylindrical 55 side-rail with its pivot end extending out therefrom at substantially right angles to the plane of the structure, said pivot-member being adjustable by a torsional movement on the side-rail, and means to pivotally 60 connect the hinge member and the pivot member together.

3. In hinges for gates and the like, having side rails and spaced apart fillers, a main hinge member applied to one of the 65 side rails, a mating member adapted to clamp the hinge member to the side-rail and hold it in fixed relation thereto, an extension member comprising two mating members clamped on an adjacent filler and having one set of their ends inserted between the adjacent ends of the hinge member and its mate, slotted holes in said inserted ends, a bolt passed through the hinge member and its mate and through the slotted holes in 70 the extension members, whereby said extension members may be adjusted to connect with the filler and the hinge member will be readily connected to the side-rail, a pivot member adjustably connected to the structure to which the gate is applied and means to 75 pivotally connect the hinge member and pivot member together.

Fairfield, Iowa, January 7th, 1922.

ALBERT H. NELLER.

Certificate of Correction.

It is hereby certified that in Letters Patent No. 1,437,736, granted December 5, 1922, upon the application of Albert H. Neller, of Fairfield, Iowa, for an improvement in "Hinges for Gates and Other Closures," an error appears in the printed specification requiring correction as follows: Page 2, line 79, claim 3, for the word "readily" read *rigidly*; and that the said Letters Patent should be read with this correction therein that the same may conform to the record of the case in the Patent Office.

Signed and sealed this 23d day of January, A. D., 1923.

[**SEAL.**]

KARL FENNING,
Acting Commissioner of Patents.
